UNITED STATES PATENT OFFICE.

URIAH S. JACKSON, OF BOSTON, MASSACHUSETTS, ASSIGNOR TO THE SUPERIOR AUTOMATIC TELEPHONE COMPANY, OF BOSTON, MASSACHUSETTS, A CORPORATION OF MAINE.

TELEPHONE-SERVICE APPARATUS.

SPECIFICATION forming part of Letters Patent No. 750,770, dated January 26, 1904.

Application filed April 22, 1903. Serial No. 153,854. (No model.)

To all whom it may concern:

Be it known that I, URIAH S. JACKSON, a citizen of the United States, and a resident of Boston, in the county of Suffolk and State of Massachusetts, have invented a new and useful Improvement in Telephone-Service Apparatus, of which the following, taken in connection with the accompanying drawings, is a specification.

10 My invention relates to that class of telephone-service apparatus that involves the use of devices by which the person using the apparatus may call up any one on the system and in so doing cut out all of the others, so 15 that there can be no interruption by a third party, and in which a step-by-step mechanism is used for calling the desired box; and it consists in combining with an apparatus of this class a dial mechanism having a pointer 20 which is constructed to be moved so as to stand at a number on the fixed dial that will indicate the number of electrical contacts that will be made by the next movement of the step-by-step mechanism; this number indicating the box to be called, and a telephone-receiver having a circuit closer and opener attached.

25 The object is to simplify the working of this class of apparatus. This object I attain by 30 the mechanism shown in the accompanying drawings, in which—

Figure 1 shows one of the telephone-boxes in elevation, its door being closed. Fig. 2 shows a box in elevation, the door being open, and parts are represented as broken away for the purpose of showing other parts more clearly. Fig. 3 shows certain details in elevation. Fig. 4 is a vertical cross-section taken on line 4-4 of Fig. 3. Figs. 5, 6, and 40 7 relate to the receiver. Fig. 8 is a diagrammatic view showing a manner of connecting the circuits of the novel features of this apparatus.

45 As my present invention relates to only a very small part of the apparatus required in this class of telephone service, it is not necessary to give a complete description of the entire mechanism, as that has already been fully

explained in previous specifications and drawings.

Briefly, the parts to which my improvements closely relate may be explained as follows: The outside case or box of my instrument is indicated by A. A door B is hinged to the case and is shown as closed in Fig. 1 and as 55 open in Fig. 2. There are as many of these boxes as there are users in the system. Each user has a number. In the present system there are fourteen of these boxes, each of which is indicated by a numeral on the dial 60 D, Figs. 1 and 2. A pointer D' moves on the dial and is made to indicate to the user that the desired or called box is in connection and may be communicated with.

The mechanism by which the calls are made 65 in this class of apparatus may be described as follows: The lever L is rigidly connected to a shaft L², and the said shaft L² is so connected to the spring driving mechanism that by depressing the said lever L the driving mechanism is ready to act upon the notched make-and-break wheel C² with a tendency to cause it when not locked to rotate in the direction of the arrow V. (See Figs. 2 and 8.) The number of the points C³ on the wheel C² is 70 75 equal to the numbers on the dial D and to the number of the boxes in the system. The pin C⁴, extending from the under side of the wheel C², serves to stop the said wheel by coming in contact with the end L' of the lever L when 80 the said lever is in its normal or resting position, as indicated in Fig. 2—that is, the wheel is stopped when it has made a complete rotation and has brought the pointer D' to "0" on the dial. The lever L has upon it a pin L³, 85 which is arranged to engage with the hook L⁹ on the bell-crank lever L¹⁰ L¹¹, pivoted at L¹². This hook-lever L¹⁰ L¹¹ is thrown into its locking position by a spring L¹³ and holds the operating or winding-up lever L in the position 90 shown in Fig. 2, so that the winding-up lever L cannot be used except when the cam-boss L⁸ is in the position shown in Fig. 2—that is, the boss L⁸ throws the end L¹¹ of the lever up, and thus forces the hooked end L⁹ away from 95 the pin L³, as shown, and thus unlocks the

said winding-up lever L. This unlocked position is the position in all of the boxes when the pointer D' is at "0." As the above-described parts are not new, they need not be 5 more fully explained.

I will now proceed to describe the parts that I think are new. These parts relate exclusively to the user's control of the service apparatus while he is talking, and with telephone-receiver in his hand with one finger of the same hand upon a push-button on said receiver he controls the entire system; but he controls it only so long as he holds the receiver in his hand with one finger upon the 10 attached push-button. Therefore the user when he has used the apparatus and lays the receiver down or takes his finger from the push-button allows the entire apparatus to 15 assume its normal condition—that is, all of the boxes will be ready for use, or, in other words, all of the levers L are unlocked and the lever of any box may be pushed down.

The user's first act is to depress the lever L of his box. As soon as this is done it will 20 start the whole mechanism of all the boxes, which will cause the boss L¹ to pass out from under the end L¹¹ of the locking-lever, and thus allow the hook L⁹ to swing into locking engagement with the pin L³ on the winding-up lever L, thus locking it in all of the boxes except the one from which the call is made. The same movement will cause the pin C⁴ to pass 25 out from under the electrode m⁸ and allow it to make an electrical contact with the electrode m⁷, Fig. 8, and thus close the circuit of the magnet M and cause the armature E¹¹ to be drawn to the magnet. This action will cause the arm E⁹, which swings on the pivot E¹⁰, to act through its pin E⁸ and draw up the 30 link E⁷, which acting through the pin E⁶ causes the hook-lever E⁴ to swing on its pivot E⁵, and thus frees the arm E, which has the pawl E² attached by the pin E³, the hook of the lever E⁴ engaging with the extension of the pin 35 E³ when the mechanism is in the position illustrated in Fig. 8; but when the mechanism is in the position shown in Fig. 3—that is, when the magnet is energized—then the hook of the lever E⁴ is not in engagement with the 40 pin E³ of the pawl E². Now the user by taking hold of the handle H, that is attached both to the pointer E' and to the plate E, may turn the said plate and pointer to the desired 45 position—that is, so that the pointer E' will point to the number of the box to be called—"6," for instance. This action will carry the pawl E² around to "6," and as the notches on the pawl-wheel C⁵ are the same in number and 50 correspond to the contact-points C³ C³ on the wheel C², to which the pawl-wheel C⁵ is rigidly attached, it is obvious that when the said wheel C² has rotated (in the direction of the arrow V) so as to make six contacts of its points C³ with the make-and-break electrode 55 G', Fig. 2, then the pin E³ of the pawl E²

will have returned to the position shown in Fig. 8—that is, so that it will be stopped and held by the hook of the lever E⁴—and box No. 6 will be put in electric communication with the box of the user. So long as the hook of the lever E⁴ holds the plate E and the contact-wheel C² in this position the user may talk with No. 6. The arrangement is such that whenever the magnet M is not energized the hook of the lever E⁴ will be in its locking position. 70

One of my improvements embodies a device connected to the receiver by which the user controls the magnet M and through it the locking hooked lever E⁴. This device is 80 fully illustrated in Figs. 5, 6, 7, and 8, and consists in a telephone-receiver in which two additional wires m¹ and m⁴ are used, which are connected to the extra binding-posts T T² of the receiver. It also consists in the circuit 85 running from the magnet M through m¹ to the fixed electrode m² in the receiver, Fig. 5, thence through the metallic spring m³ to wire m⁴, thence to post T² and through wire m⁵ to line W to source of electricity, thence through 90 line W', wire m⁶ to electrodes m⁷ m⁸ and wire m⁹ back to magnet M.

The make-and-break device in the receiver consists of a spring-electrode m³, attached at one end to the boss T³, Fig. 5, and acted upon at the other end by the push-button P. The parts are so arranged that when the push-button is not depressed by the user then the spring-electrode m³ is in electrical contact with the fixed electrode m² and the circuit through the magnet is completed, the magnet is energized, and the hook-lever E⁴ is drawn away from the pin E³ of the pawl E², thus allowing the contact-wheel C² to rotate; but when the push-button P is depressed then the circuit is opened 100 and the magnet M is left unenergized, as indicated in Fig. 8, and the contact-wheel C² is locked. When the user has given his message, he releases the push-button P, and thus closes the circuit through the magnet, which 105 unhooks the lever E⁴ and allows the wheel C² to return to its normal or "0" point and readjust all of the mechanism of all the boxes to their normal position ready for future use. 110

I claim—

1. In a telephone-service apparatus: a circuit make-and-break wheel and mechanism for operating the same; a pawl-wheel attached to the said circuit make-and-break wheel and having the same number of notches as there 120 are make-and-break points on the said circuit make-and-break wheel; a pawl-arm constructed to turn on the axis of the said make-and-break wheel and having a pawl adapted to engage with the notches of the said pawl-wheel and also having a pointer to indicate on a numbered dial the position of the said pawl in relation to the points of the make-and-break wheel, whereby the number on the dial at 125 which the said pointer stands will indicate the 130

- box to be called; the said numbered dial and an electrically-controlled mechanism by which the said arm and its pawl are held or released; substantially as and for the purpose set forth.
- 5 2. In a telephone-service apparatus: a circuit make-and-break wheel and mechanism for operating the same; a pawl-wheel attached to the said circuit make-and-break wheel and having the same number of notches as there are make-and-break points on the said circuit make-and-break wheel; a pawl-arm constructed to turn on the axis of the said make-and-break wheel and having a pawl adapted to engage with the notches of the said pawl-wheel and also having a pointer to indicate on a numbered dial the position of the said pawl in relation to the points of the make-and-break wheel, whereby the number on the dial at
- which the said pointer stands will indicate the box to be called; the said numbered dial; an electrical circuit constructed to operate said pawl-arm; and a telephone-receiver having make-and-break electrodes connected with said circuit and having an attached push-button by which said make-and-break electrodes are controlled; substantially as and for the purpose set forth.
- In testimony whereof I have signed my name to this specification, in the presence of two subscribing witnesses, on this 17th day of April, 30 A. D. 1903.

URIAH S. JACKSON.
